CASE INVERTER

Robert J. Mallow, North Tonawanda, and Fred W. Stratman, East Aurora, N. Y., assignors to Pressed Steel Car Company, Inc., Chicago, Ill., a corporation of Pennsylvania

Application November 29, 1952, Serial No. 323,214

8 Claims. (Cl. 198—33)

1

The present invention relates to case inverters and particularly to inverters for cases such as are commonly used for milk bottles. It is frequently desirable to provide a means for inverting milk bottle cases in order that the cases may be cleaned or for other reasons and the present invention is concerned with a mechanism which may be utilized for this purpose and which inverts the cases as they travel along a belt conveyor.

More particularly still the present invention relates to such an inverter which may be readily raised out of the path of cases so that the cases may proceed along the conveyor without being inverted when that is desirable.

As will be obvious, a pair of inverters in accordance with the present invention may be situated along the conveyor so that cases may be fed to a cleaning machine for example in an upright position, inverted prior to reaching the cleaning zone, and again inverted after being cleaned and discharged in the same position in which received.

It is an object of this invention to provide an inverter for cases such as milk bottle cases and the like.

It is another object of the invention to provide such an inverter which may be installed at any desired point along a conveyor and which will serve to invert cases as they travel along that conveyor.

It is a further object of the invention to provide an inverter as described above which may be rendered inactive without the necessity of removing it from its location on the conveyor.

It is a still further object of the invention to provide an inverter of the type mentioned which is extremely simple mechanically and which is readily manufactured and easily maintained and serviced.

It is a still further object of the invention to provide an inverter of the type mentioned which is readily installed for cooperation with an existing conveyor and which may be moved from one location to another with ease.

Other objects and features of the invention will be apparent when the following description is considered in connection with the annexed drawings, in which:

Figure 1 is a side elevation of a case inverter in accordance with the invention;

Figure 2 is a vertical cross-sectional view of the device of Figure 1, the view being taken on the plane of the line 2—2 of Figure 1; and

Figures 3, 4, 5 and 6 are schematic diagrams

2

illustrating various stages in the operation of the device as the case is inverted.

Referring now to the drawings and particularly to Figures 1 and 2, there is shown therein a framework generally designated 10 and composed of the flanged plates 11 and 12, the plates being spaced apart from each other and having bushings therein in which various shafts hereinafter described are rotatably mounted. The frame 10 is supported upon legs 13, the height of the frame being preferably adjustable by adjusting its position on the supporting legs.

An auxiliary base member 14 is fixed to the plate 12 and on this base is mounted a driving motor 15 and a gear reduction unit 16, the unit being coupled to the motor by means of the flexible coupling 17. Journalled adjacent the lower corners of the plates 11 and 12 are two shafts 18 and 20. Shaft 18 carries two sprocket wheels 21 and 22 thereon and shaft 20 in a similar manner carries two sprocket wheels 23 and 24. A pair of conveyor chains 25 and 26 extends about the pairs of sprocket wheels 21, 23, 22, 24 forming essentially a single conveyor chain which

25 chain serves to cooperate with the other mechanism about to be described to cause the inversion of a case as it passes between the plates 11 and 12.

At 27 is shown a conveyor belt or chain which is utilized to feed cases to and remove cases from the inverter mechanism the mechanism being installed in such a manner that the chain 27 lies between the chains 25 and 26 and the upper reach of the chains 25 and 26 is slightly above the upper reach of the chain 27.

The drive is so adjusted that chains 25 and 26 run more rapidly than does chain 27 and thus cases which are travelling on chain 27 are taken from that chain by the chains 25 and 26 and because of the greater speed of the chain 27 a space is provided between successive cases on the conveyor chains 25 and 26.

As is clearly apparent in Figure 2 the chains 25 and 26 are driven by means of a sprocket wheel 28 mounted on shaft 20 which is connected by means of chain 30 to a similar sprocket wheel 31 on the shaft 32 of the gear reduction unit 16.

A shaft 33 is journalled in the plates 11 and 12 and is driven by means of a chain 34 passing over sprocket wheel 35 on shaft 32 and sprocket wheel 36 on shaft 33. Rotatably mounted, one on either end of the shaft 33, is a pair of arms 37 which arms at their forward ends have rotatably mounted therein a shaft 38. Shaft 38 ex-

3

tends through arcuate openings 40 in the plates 11 and 12 respectively and has mounted thereon between plates 11 and 12 a rubber covered or other suitable friction surfaced roller 41. Shaft 38 is driven from shaft 33 by any suitable means such for example as the chain 42 cooperating with sprockets 43 and 44 respectively fixed to shafts 33 and 38.

Arms 37 extend to the left of the shaft 33 as seen in Figure 1 and have pivotally fixed thereto the counterweights 45. These counterweights do not fully compensate for the weight of the mechanism at the right-hand end of the arms 37 so that the shaft 38 and roller 41 thereon normally occupy the lower position as is shown in full lines in Figure 1.

It will be noted that the drive arrangements are such that all of the various shafts mentioned rotate in the same direction which in the present instance is clockwise as viewed in Figure 1.

As has been indicated hereinabove cases are placed on the belt or chain 27 and upon reaching the chains 25 and 26 are taken from the belt 27 and moved more rapidly toward the roller 41. When a case reaches the position indicated in Figure 1 it is stopped by the roller 41. At the same time, since roller 41 is rotating in a clockwise direction as seen in Figure 1 and is coated with friction material, it tends to raise the leading edge of the case to a position such as is indicated in Figure 3. As the forward end of the case rises the rearward end is permitted to move with the conveyor chains 25 and 26 and after a short time the case reaches the position indicated in Figure 4. Continued movement of the chains 25 and 26 coupled with continued rotation of the roller 41 serves to first cause the case to stand on its end and immediately thereafter to cause the case to fall over in a completely inverted position the various stages being indicated in Figures 5 and 6. As is clearly shown by Figures 5 and 6 the case is moved sufficiently rapidly by the conveyor belts 25 and 26 so that the roller 41 does not rest upon the rear edge of the inverted case but instead moves downward through its arcuate path and extends across from plate 11 to plate 12 in the path of a subsequent case on the conveyor chains, that is, in position to perform the same operation on a following case.

In the normal installation the chain 27 is a main conveyor chain and extends beyond the chains 25 and 26 so that cases which have been inverted are returned to the chain 27 to be conveyed to any subsequent operation which is customary or desirable, as for example a cleaning operation.

The inverter mechanism may be rendered ineffective by adding weight to the counterweights to thereby hold the roller 41 above cases which are passing through on the conveyor and, of course, while the roller remains in this position no inverting action can occur.

As will be obvious the entire inverter structure may be readily removed from its position astride the main conveyor and the main conveyor thus returned to its prior condition, the inverter being of course usable in other locations. In other words, the entire inverter unit is portable and may readily be moved from one location to another.

While preferred embodiments of the invention have been described it will be understood that various modifications of this invention may be made and therefore we wish to be limited not by

the foregoing description but by the claims granted to us.

What is claimed is:

1. In a mechanism for inverting cases, in combination, a conveyor, a roller extending transversely of the conveyor and in the path of a case moving on the conveyor, means mounting said roller for movement toward and away from said conveyor, and means for rotating said roller in a direction to elevate the leading end of the case on the conveyor as the conveyor advances the case until the rearward end of the case is on the conveyor, and to then complete the inversion as the conveyor continues to advance the case.
2. A device as claimed in claim 1, characterized in that said roller is surfaced with friction material.
3. A device as claimed in claim 1, characterized in that said roller is pivotally mounted to move in an arcuate path toward and away from said conveyor.
4. A device as claimed in claim 3 characterized in that said roller is mounted on one end of a pair of lever arms and the opposite ends of said lever arms carry counterweights, said counterweights being of slightly lesser mass than said roller and lever arm supports therefor whereby said roller tends to approach said conveyor but is readily lifted therefrom as a box rises toward a position in which its end rests on said conveyor.
5. A device as claimed in claim 1 characterized in that said roller moves in an arcuate path toward and away from said conveyor, said roller being rotatably mounted at one end of a pair of lever arms, said lever arms being pivotally mounted to provide for said arcuate path and further characterized in that said roller is driven through drive pulleys mounted concentrically with the pivot point of said levers.
6. A device as claimed in claim 1 characterized in that said conveyor means is supported on a framework and is adapted to be positioned adjacent a feed conveyor with the upper reach of said conveyor slightly elevated above the upper reach of the feed conveyor and further characterized in that the said conveyor has a greater linear speed than the feed conveyor whereby a line of cases on the feed conveyor arrives at the inverting position with spaces between the cases of the line thereby assuring that said inverting roller will be in position to make contact with the forward wall of each case.
7. In a device of the class described, in combination, a framework comprising a pair of spaced supporting plates, a pair of shafts rotatably mounted one at either end of said pair of supporting plates and extending therebetween, a pair of endless conveyors mounted on said shafts between said plates and one adjacent each of said plates, said conveyors being adapted to lie one on either side of a feed conveyor with the upper reaches thereof slightly above the upper reach of the feed conveyor, a roller coated with friction material extending between said plates and above said conveyors, the axis of said roller being parallel to the axis of said conveyor drive shafts, a shaft extending between said plates, means comprising a pair of levers pivotally mounted on said shaft for mounting said roller in the position aforesaid, and drive means supported on said framework, said drive means driving both said conveyors and said roller whereby a case moving with said conveyors is stopped by said roller, said roller then elevating the forward

wall of said case while said conveyors continue to advance the case, the roller pivoting about said shaft as the forward wall is elevated, thereby causing the case to attain a position wherein the rear wall rests on said conveyors, said roller being then supported by the forward wall and continued movement of the conveyor and said roller causes the completion of inversion of the case as it moves beyond the arcuate path of said roller.

8. A device as claimed in claim 7 characterized

10

in that the driving means for the roller comprises a pair of pulleys one mounted on the roller shaft and one mounted coaxially with the pivot for said lever arms, thus assuring rotation of the roller irrespective of its position along its own arcuate path.
